United States Patent Office

Des. 215,833
Patented Nov. 4, 1969

215,833

BODY FOR MOTOR VEHICLES OR THE LIKE

Eugene T. Daniel, Walnut, Calif., assignor to Safari Enterprises, Inc., a corporation of California

Filed Oct. 14, 1968, Ser. No. 13,992

Term of patent 14 years

Int. Cl. D12—08

U.S. Cl. D14—3

Fig. 1

Fig. 2

Fig. 3

Fig. 4

Fig. 5

FIGURE 1 is a perspective view of the body for motor vehicles, or the like;

FIGURE 2 is a left side elevation thereof, the right side being identical thereto;

FIGURE 3 is a top plan thereof;

FIGURE 4 is a front perspective thereof; and

FIGURE 5 is a rear perspective thereof.

The steering wheel, seats and tires are shown in broken lines for illustrative purposes only.

I claim:

The ornamental design for a body for motor vehicles or the like, as shown and described.
